UNITED STATES PATENT OFFICE.

ROBERT H. CROZIER, OF RANGOON, BURMA

OIL-SHALE RETORT.

Application filed September 5, 1923. Serial No. 661,023.

To all whom it may concern:

Be it known that I, ROBERT HENRY CROZIER, a subject of the King of Great Britain and Northern Ireland, and residing at Rangoon, Burma, have invented a certain new and useful Improvement in Oil-Shale Retorts, of which the following is a specification.

This invention relates particularly to the treatment of oil-shale and similar solid oil-yielding materials which do not become soft or plastic, but retain their ability to move freely by gravitation when heated in a confined space; the invention is, however, also applicable to the treatment of oil-yielding materials which may be kept in continuous motion by mechanical means.

More particularly, the invention relates to a process of and apparatus for the recovery of oils in a semi-refined condition, direct from oil-shales and similar oil-yielding materials, by the progressive application of heat.

It is well known that, by the application of heat to oil-shale, torbanite, coal and other similar carbonaceous substances, in a process of destructive distillation, mixed oils of a paraffin, naphthalene, or asphaltic base may be obtained. In the ordinary methods of retorting, these mixed oils are recovered in the form of crude oil containing an excessive quantity of "cracked" and unsaturated compounds owing to the manner in which the process is conducted.

It has now been discovered that by the progressive application of heat to the oil-yielding material in a suitable retort or apparatus the process of decomposition may be so controlled as fractionally to distill the various main products direct from the material being treated, the products so obtained being of superior quality and requiring less treatment in subsequent refining than oils produced by older methods of retorting.

In the accompanying drawings, which illustrate an apparatus or retort according to the invention, and in which like reference letters indicate corresponding parts in the several figures, Fig. 1 is a plan, Fig. 2 is a cross section on the line A—B of Fig. 1, Fig. 3 is a cross section on the line C—D of Fig. 1, and Fig. 4 is a cross section of the conical vapor trap and radial steam spray hereinafter referred to.

In the drawings *a* denotes a cast-iron upright retort comprising superposed cylindrical sections in which the shale or oil-yielding material is heated and which is provided with a series of inclined flues *b* crossing the retort diametrically.

The heating of the retort may be accomplished by burning extraneous fuel or the fixed gas produced in the process of distillation and conducting the heated products of combustion, by means of the annular flues *c* which encompass the retort, to the various sections to be heated. The circulation of the heated gases through the external flues *c* is controlled by the dampers *d* and the circulation through the internal flues *b* is controlled by the dampers *d*²; or the heat may be supplied under control to the individual sections of the retort by means of annular gas burners *e*.

The retort is provided with a number of vapor traps *f* fitted to exit pipes *g* by means of which the oil vapors may be conducted from the retort as formed and led through dust traps *h* to any suitable form of condensing apparatus. The vapor exit pipes *g* are insulated in their passage through the external heating flues *c* by means of asbestos or other suitable material, in order that super-heating of the vapors and consequent "cracking" may be avoided. The conical vapor traps *f* are arranged at such intervals in the retort as is indicated by the temperature gradient to be maintained and the required number and boiling points of the fractions to be recovered. The bottoms of the conical vapor traps are provided with annular ducts or pipes *i* perforated in such manner as to permit the introduction of steam into the retort in the form of radial sprays or screens. The steam screens substantially prevent the mingling of the vapors produced in any section of the retort with those produced in adjacent sections. Steam may also be introduced at the bottom of the retort through perforations opening into the annular steam box *j*.

The charging of the material to be treated and the discharging of the spent residue may be effected by any suitable apparatus which provides an effective seal against the escape of gases from the retort.

In the process of treatment the material is broken to a suitable size and charged in at the top of the retort, the spent residue be-

ing continually discharged from the bottom. As the material passes downwards through the various sections of the retort, it progressively yields its oil constituents, according 5 to the increasing temperatures through which it passes. The temperature gradient of the retort is regulated so that the low-boiling-point benzine-naphtha vapors may be drawn from the top exit pipe; the kerosene, burning oil, intermediate oil, and heavy 10 oil and paraffin-wax vapors being drawn from subsequent lower exit pipes, according to the heat regulation, as desired.

I claim:—

- 15 1. Apparatus for the fractional distillation of oil direct from solid oil-yielding material comprising a vertical retort, an external flue surrounding the retort and serving as an external heating chamber, partitions 20 separating the said external flue into separate chambers and internal flues extending at an angle to the horizontal through said retort and forming a connection between adjacent chambers of the external flue.
- 25 2. Apparatus for the fractional distillation of oil direct from solid oil-yielding material, comprising a vertical retort, means

for applying heat to the retort including a surrounding flue, said flue divided into sections, said sections controlled by dampers, 30 and internal flues extending from section to section and forming a connection between adjacent sections of the surrounding flue.

3. Apparatus for the fractional distillation of oil direct from solid oil-yielding material, comprising a vertical retort, means for applying heat to the retort including a surrounding flue, said flue divided into sections, said sections controlled by dampers, 35 internal flues extending from section to section and forming a connection between adjacent sections of the surrounding flue, and dampers controlling said internal flues.

4. Apparatus for the fractional distillation of oil direct from solid oil-yielding material, 40 comprising a vertical retort, means for producing radially extending steam screens within said vertical retort and a plurality of vapour traps vertically spaced, said 45 vapour traps disposed axially of said vertical retort.

In testimony whereof I have signed my name to this specification.

R. H. CROZIER.
